UNITED STATES PATENT OFFICE.

GEORGE FRANKLIN BUTTERFIELD, OF STONEHAM, MASSACHUSETTS.

BATH-TUB.

SPECIFICATION forming part of Letters Patent No. 565,836, dated August 11, 1896.

Application filed June 6, 1895. Serial No. 551,885. (No model.)

To all whom it may concern:

Be it known that I, GEORGE FRANKLIN BUTTERFIELD, of Stoneham, in the county of Middlesex and State of Massachusetts, have 5 invented certain new and useful Improvements in Bath-Tubs, of which the following is a full, clear, and exact description.

The object of the invention is to provide a new and improved bath-tub which can be 10 readily divided to form a foot-bath or children's tub in the supply end, to permit of conveniently bathing children, and to save a considerable quantity of water, which is otherwise necessary for filling the entire tub.

15 The invention consists principally of a gate hung on one side of a bath-tub near the foot end, the said gate being adapted to close the upper or head portion to the water-supply.

20 The invention also consists of certain parts and details and combinations of the same, as will be fully described hereinafter, and then pointed out in the claims.

25 Reference is to be had to the accompanying drawings, forming a part of this specification, in which similar characters of reference indicate corresponding parts in all the figures.

30 Figure 1 is a perspective view of the improvement. Fig. 2 is a transverse section of the same, looking toward the head portion; and Fig. 3 is a like view looking toward the foot portion.

35 The improved bath-tub A, made of suitable material, is provided with a foot or lower part A' and a widened head portion A², arranged to permit the user to have perfect freedom of his arms while bathing in the tub. In the lower end of the tub A are arranged the usual hot and cold water supply pipes B, and near 40 this lower end is hung a gate C, connected by hinges D with one side of the tub. The gate C extends the full height of the tub A, and is adapted to fold to one side thereof when not in use, as indicated in dotted lines in Fig.

45 1. When the gate C is swung open, as shown in the drawings, it forms a transverse partition in the tub for dividing the lower or foot portion A' from the head portion A² and for forming a foot-bath or children's tub in the 50 lower end of the bath-tub. The gate C when swung open rests against cleats E, secured to the sides and bottom of the tub, so that when

the gate is in this position and the water is turned on through the supply-pipes B, then this lower portion of the tub is filled with water for a foot-bath or for bathing children, as the case may be. On the side on which the hinges D are attached is arranged a seat F, extending outwardly and upwardly from the top edge of the side of the bath-tub, to be 55 supported on suitable brackets G, attached to the outer face of this side of the tub. By this arrangement a person desiring to take a foot-bath can conveniently seat himself while taking the foot-bath.

60 It will be seen that by the arrangement described but a small amount of water is required for taking a foot-bath or for bathing children, as the upper or head portion is shut off to the water supply by the gate C, which 65 extends transversely in the tub and forms a partition therefor. When the tub is to be used for a regular bath, then the gate C is swung to the side of the bath-tub on which it is hinged, so as to be completely out of the 70 way.

75 It is understood that when the gate closes the head portion to the water-supply and water passes into the foot end of the tub. Then the gate C is firmly pressed to its seat on the 80 cleats E by the weight of the water, so that leakage of the water into the upper head portion of the tub is not liable to take place.

Having thus fully described my invention, I claim as new and desire to secure by Letters Patent—

85 1. A bath-tub provided with a gate hinged at one edge to the inner surface of the tub, whereby the gate can be swung to form a transverse partition to divide the tub into 90 compartments, or to be folded against the inner surface of the tub when not in use, substantially as described.

95 2. A bath-tub provided, at one side of the center of its length, with a gate hinged at one edge to the inner surface of the tub to swing in direction of the water-supply end thereof, whereby the gate can be swung to divide the tub into two unequal compartments, and when so swung is adapted to be held firmly 100 to its seat by the pressure of the water in the smaller compartment, substantially as described.

3. A bath-tub provided with a gate hinged

to the inner face of one side of the tub to swing across the same and divide the tub into compartments, the said gate swinging in the direction of the water-supply end of the tub, 5 and cleats on the inner surface of the tub and against which the gate when closed is adapted to be tightly pressed by the pressure of the water in the said end compartment, substantially as described.

10 4. A bath-tub having an elongated body portion and a widened head portion, and pro-

vided with a gate hinged to the inner surface of the body portion a short distance from its water-supply end, said gate being near the foot end of the tub and adapted to be swung 15 across the same to form a foot or child's tub at the lower end of the body portion, substantially as described.
